UNITED STATES PATENT OFFICE

2,285,882

TIME DELAY TRANSFER MECHANISM

Herbert H. Andersen, Beverly, and Donald G. Cameron, Lynn, Mass., assignors to General Electric Company, a corporation of New York

Application November 7, 1939, Serial No. 303,255

12 Claims. (Cl. 171—268)

Our invention relates to dual rate meters and concerns particularly apparatus arranged for metering electric current at lower rates during certain times of the day or under certain conditions.

It is an object of our invention to provide a dual rate meter with a mechanism assuring the central station customer that he will not be charged at an excessive rate in case of voltage failure on the system upsetting the normal division of time between high and low rate registers.

Another object of our invention is to provide a mechanism for maintaining a meter at the lower rate setting regardless of subsequent conditions in the electrical system after a voltage failure or an interruption in service has occurred. Other and further objects and advantages will become apparent as the description proceeds.

In carrying out our invention in its preferred form we interpose a mechanism in the linkage for shifting the registers from high rate to low rate setting, such that in case of voltage failure the low rate setting continues until the apparatus is reset, unless the voltage failure is of such a short duration as not to be of consequence in causing excessive charges being levied on the central station customer.

The invention will be understood more readily from the following detailed description when considered in connection with the accompanying drawing and those features of the invention which are believed to be novel and patentable will be pointed out in the claims appended here-to. The single figure of the drawing is an exploded perspective view of one embodiment of our invention partially distorted and rearranged for the sake of clarity.

Our invention may be utilized in connection with a dual load meter of the type described in United States Patent 2,132,256—Cameron. The apparatus described in the present application is similar to that disclosed in the Cameron patent with the exception that we add a time delay transfer mechanism referred to generally by the numeral 10, parts of which replace the rigid connection between the bushing 55 and the shift lever 58 of the Cameron patent. The shift lever 58 of the Cameron patent corresponds to the shift lever 58' of the present application and is actuated by the time switch 13 to bring one or the other of the two sets of register dials 24 or 25 into operation according to the time of the day. Since at certain times of the day a central station can afford to sell electric power at lower rates, one of the sets of dials is referred to as the low rate register, and the power consumed when

this register is in operation is charged at a lower rate than the power consumed when the other set of dials is in operation. In order to protect the central station customer, that is, the electricity consumer, against continuance in operation of the high rate dials during a period when the customer should be charged the low rate, a time delay mechanism is provided for connecting the low rate dials in case of interruption of operation of the time switch as by reason of temporary voltage failure, for example. As will be explained more in detail hereinafter, in case of interruption in electric service, the mechanism 10 renders the connection between the bushing 55 and the shift lever 58' ineffective, in order to cause the low rate dials to be continued in operation indefinitely until the apparatus is corrected and reset by the representative of the central station company.

20 The portions of the apparatus of the present application common to the aforesaid Cameron patent are, for the sake of completeness of disclosure, described as follows: There is a power-responsive integrating mechanism or watt-hour meter unit 11, a double-dial register 12, and a time switch unit 13, with connections to a source of electric current or power 14, to a water heater 15, or other relatively large and constant wattage load, and connections to a variable wattage load 16, such as lights and appliances which may be turned on and off according to the needs of the customer whose electricity load is metered by the apparatus.

35 The watt-hour meter unit 11 is of the well-known conventional design, having a voltage or pressure winding 17 connected across the current source 14, current coils 18 connected between input terminals 19 and output terminals 20 so as to carry the load currents, an induction disk 21 acted upon by windings 17 and 18, and a shaft 22 supporting the disk 21 and carrying a worm wheel or helical threads 23 for driving the dials of a register through suitable gearing.

40 The register 12 is of the double-dial type having two independent dials or sets of dials 24 and 25, including driving shafts 26 and 27, respectively, and gearing (not shown) for converting rotation of the driving shafts into appropriate rotation of the dial pointers. The dials 24 and 50 25 may be referred to as high rate and low rate dials, respectively. A horizontal shaft 28 is provided, carrying a worm gear 29 meshing with the worm 23, and carrying a worm wheel or threaded portion 30. The shafts 26 and 27 carry 55 worm gears 31 and 32, respectively, adapted to

mesh with the worm 30. The ends of the shafts 26 and 27 at the register 12 are so supported as to permit slight lateral movement of the ends carrying the gears 31 and 32. The latter ends are supported in bearings carried by a bifurcated arm 33 secured to a rod 34 journaled in stationary bearings, not shown, but supported by the register 12.

To prevent coasting of either dial 24 or 25 while disengaged from the worm 30 and to prevent falsification of the dial readings, a pair of detents 35 is provided. The detents 35 may be composed of resilient strips, each secured at one end to a stationary portion of the apparatus supported by the register 12 and bent at the other end toward the gears 31 and 32 to form spurs 36 adapted to fit between adjacent gear teeth. It will be understood that the arrangement of the arm 33 and the positions of the shaft 28 and the detents 35 are such that one or the other of the gears 31 and 32 is in mesh with the worm 30, being then clear of the associated detent 35, whereas the gear not in mesh with the worm 30 is engaged by one of the detents 35. Thus, dial readings are prevented from changing except by operation of the meter unit 11.

In order that it will be unnecessary to examine the interior of the mechanism and study its construction to determine which of the dials 24 and 25 is at the time connected or in which position the time switch 13 is, a target or indicator 37 is provided and an aperture 37' is cut in the front plate 38 of the register 12 for the purpose of showing the existing condition of the apparatus in this respect.

Suitable means are provided for indicating a distinction between the dials 24 and 25. For example, their pointers 39 and 40 may be painted distinctive colors such as black and red and the target 37 may be divided into two areas 41 and 42, painted red and black, respectively. The target 37 is arranged to drop into the position exposing the red 41 when the gear 32 of the red pointer dial 25 is in mesh and to rise into the position exposing the black 42 when the gear 31 of the black pointer dial 24 is in mesh. In the arrangement shown, the target 37 is part of a bell-crank lever 43 mechanically connected by a pin 44 and a crank 45 to the rod 34 carrying the arm 33. As will be explained more in detail hereinafter, the bell crank 43 is operated by the time-switch unit 13 to shift the dial connection and the indicator position at the desired times of the day.

The time-switch unit 13 includes a timing motor 46 connected across the meter input terminals 19, a rotatable time dial 47, a train of gears 48 including a slip clutch 49 for connecting the motor 46 to the dial 47, a stationary pointer 50, and a snap-action movable member 51 for operating both a switch 52 and the bell-crank lever 43 of the register 12. For the purpose of operating the movable member 51, the dial 47 carries one or more "on" riders 53 and one or more "off" riders 54, all of which are adjustable in position on the periphery of the dial 47. The movable member 51 is pivotally mounted by being secured to a rotatable bushing 55 fitting over a post 56 attached to a stationary plate (not shown). There is also a shift lever 58' carrying a pin 59 for engagement with a slotted portion of the bell-crank lever 43.

Means involving our present invention and including portions of the time delay transfer

mechanism 10 are interposed between the bushing 55 and the shift lever 58' for the purpose of causing the shift lever 58' to remain in the low rate position corresponding to the "on" position 5 of the time switch indefinitely in case of voltage failure, as will be explained more in detail hereinafter.

The member 51 is arranged to be moved between two limiting positions, designated "on" 10 and "off" positions, by snap action. To this end, a member 60, having a transverse projection 61 at one end and a spring-receiving eye 62 at the other end, is pivotally mounted upon the member 51. The projection 61 is of just sufficient 15 length to engage the "off" riders 54 but not the "on" riders 53. It will be observed that the "off" 20 riders 54 have extending fingers lying behind the plane of the dial 47, whereas the "on" riders 53 have extending fingers lying in front of the 25 plane of the dial 47. There is a biasing spring 63 fastened at one end in the eye 62 of the member 60 and fastened at the other end to a pin (not shown) on the stationary plate (not shown). The member 51 is notched at the end 30 to form a step-shaped configuration with an "on" notch 64 at a greater distance from the pivot post 56 than the "off" notch 65. There is a spring-biased detent 66 cooperating with the stepped notches 64 and 65 and the detent 66 is 35 connected by a pivot shaft 67 to an arm 68 in front of the dial 47. The arm 68 carries a pin 69 of just enough length to engage the "on" 40 riders 53 but not the "off" riders 54.

The switch 52 comprises resilient switch 35 blades 70, carrying movable contacts 71, stationary contacts 72, insulating thrust members 73, and a rod 74 projecting transversely from the movable member 51.

In order that the time-switch unit 13 may be 40 reset, a slotted adjusting knob 76 is provided which may be turned by a suitable implement, such as a screw driver, or a suitable setting tool (not shown).

The apparatus illustrated in the present application differs from that shown in the afore- 45 said Cameron patent in that the shift lever 58' is not rigidly attached to the bushing 55 but is pivotally mounted at the end of a crank 90 secured to the bushing 55 so that the lever 58' 50 and the crank 90 together form a jointed shift lever corresponding to the rigidly connected shift lever 58 of the Cameron patent. Means are provided for causing the shift lever 58' normally to maintain a fixed position relative to the 55 crank 90 so that the two together form a rigid lever, but under certain conditions this means permits such rigid lever to break or bend so as to cause the pin 59 to remain at the right hand low rate position even when the crank 90 is 60 turned to the left by the operation of the time switch unit 13. This means is the time delay transfer mechanism which is referred to generally by reference numeral 10. It includes a member 91 pivotally mounted on the bushing 55 65 carrying a pin 92 upon which is pivotally mounted a limit lever 93 having a notch 94 in one end thereof. Cooperating with the notch 94 and adapted to fit into it is a tip 95 formed in the end of a bell crank 96 formed as a continuation of the lever 58'. The lever 58' also has a transverse arm 97 and a spring 98 is connected 70 between the arm 97 and the limit lever 93 for the dual purpose of bending the shift lever 58' to the right-hand or low-dial setting when the 75 tip 95 is out of engagement with the notch 94 of

the lever 93, and resiliently holding the limit lever 93 in an upward position.

Means are provided for normally holding the limit lever 93 and the shift lever 58' in the relative positions shown in which the tip 95 and the notch 94 are in engagement. This means takes the form of a latch 99 carried by the pivoted member 91 and a member 100 which takes a downward position when the apparatus is energized and includes a slot 101 for receiving the latch 99. The edge 102 of the slot 101 is provided for preventing the latch 99 from swinging to the left and permitting the member 91 to turn from the position in which the tip 95 and the slot 94 are in engagement and the lever 58' in effect travels as a unit with the arm 90 when the bushing 55 is rotated. If desired hooks 103 and 104 may be provided on the members 91 and 93, respectively, for limiting the relative travel of these members. A pin 105 is provided for limiting the extent of clockwise rotation permitted to the shift lever 58' when the member 91 is in the angular position shown in which the tip 95 and the notch 94 are intended to be in engagement.

The geometrical relationship between the parts is such that if the angular position of the member 91 should be relaxed slightly, the inside edge 106 above the elbow of the shift lever 58' would strike the pin 105 to prevent further rotation of the shift lever 58', but the moment arms from the pivots of the levers 58' and 93 to the points of attachment of the ends of the spring 98 and to the tip 95 and the notch 94 are such that the tip 95 bearing against the notch 94 would not deflect the lever 93 and normally the shift lever 58' does not have occasion to strike the pin 95 when the member 91 is in its normal or operating position shown. However, the length of the lever 93 is such that when the member 91 is unlatched and turns to the left the slot 94 rides off the tip 95 and permits the tip to deflect to the right.

The slotted member 100 is so arranged that it is caused to remain in the downward position normally and caused to bend upwards in case of voltage failure interrupting time switch operation. To this end the member 100 is composed of temperature responsive bimetallic-strip material having a relatively low thermal coefficient of expansion material below and a relatively high thermal coefficient of expansion material above, for example, iron and copper, respectively, so that when the strip 100 is heated it bends downward and holds the latch 99 and when the strip cools off it bends upward and releases the latch 99. For maintaining the strip 100 normally heated, a heating coil 107 is provided directly connected to the strip 100 by means of a suitable bracket 108 composed of heat conducting material, such as metal. The strip 100 is supported at the left-hand end 109, but for the sake of ambient temperature compensation the support is not made rigid but is subjected to the influence of a temperature compensating strip 110 for maintaining the location of the right-hand end of the strip 100 regardless of ambient temperature. The strips 100 and 110 are connected at the left-hand ends to a thermally insulating block 111 which is pivotally secured to a pin 112 connected to the stationary portion of the apparatus, not shown, and the compensating element 110 is also in the form of a bimetallic strip composed of materials having relatively high and low thermal co-

efficients of expansion, for example, copper and iron, respectively. The right-hand end of the strip 110 is adjustably secured by means of screw 113 threaded into the stationary portions of the apparatus 114, and made rotatable to permit proper adjustment of the temperature responsive latching mechanism to cause the latch 99 to remain engaged so long as there is no voltage failure and to adjust the amount of time delay. For energizing the heater coil 107, it is connected by means of a pair of conductors 115 to leads 116, which are connected to the source of electric power 14 and energize the time switch unit 13. Preferably the strips 100 and 110 are not placed one above the other, but are staggered or if desired a shield may be employed to prevent heat dissipated by the strip 100 from affecting the compensator 110.

For the purpose of permitting resetting of the time delay transfer mechanism after a voltage failure has occurred and has been corrected, the shaft 117 carrying the time switch adjusting knob 76 is made axially movable and carries at its inner end a cone-shaped enlargement 118. Cooperating with the cone-shaped enlargement 118 is an arm 119 secured to the pivoted member 91. The time switch gear 82 in the apparatus of the present application is not rigidly connected to the shaft 117 of the time switch adjusting knob 76 but is provided with a keyway 120, and a key 121 dimensioned for a loose fit in the keyway 120 is secured to the shaft 117. The key 121 is so placed that in order to reset the time switch unit 13 by means of the knob 76 it is necessary to depress the knob 76 inward, sliding the key 121 into the keyway 120 and bringing the conical enlargement 118 in engagement with the arm 119 of the member 91 to move it clockwise angularly into the position illustrated. For resiliently biasing the member 91 to the counterclockwise angular position, that is, away from the normal position, a spring 122 is provided and connected between the lever arm 119 and a transverse arm 123 formed on the member 51 of the time switch unit 13.

The operation of the apparatus when there is no voltage failure and when the crank 90 and the shift lever 58' are held together rigidly to form a rigid unit driven by the bushing 55 is as follows:

Let it be assumed that there is a valley in the central station load curve between two and five-thirty in the afternoon and that the central station can well afford to furnish power at a lower rate during this period if it can obtain additional load during this period, particularly if it can be assured that such extra load cannot be connected between five-thirty and nine-thirty, the assumed peak load period. One of the "on" riders 53 is clamped at two o'clock and one of the "off" riders 54 is clamped at five-thirty on the dial 47, which rotates counterclockwise. Assuming that the dial is initially in the position shown in Fig. 1, the first event will be that the rider 53 will strike the pin 69, pushing it downward. The detent 66 will thereby be rotated clockwise against the force of its spring, the member 51 will be released, the spring 63 will draw the member 51 upward, and two functions of the member 51 will be performed. First, the switch blades 70 will be allowed to rise, closing the switch contacts 71-72 and connecting the water heater 15 to the supply source 14 through the meter unit 11. Second, the shift lever 58' will be rotated to the right. The latter action,

in turn, will move the target 37 to bring the red portion 41 in view and will raise the arm 33 to bring the gear 32 in mesh, connecting the low rate red-pointer dial 25 to the meter unit 11. It will be understood that the meter reader will note separately the readings of the dials 24 and 25 and that the central station will charge the kilowatt hours recorded on the dial 25 at a lower rate than those recorded on the dial 24.

Just before five-thirty, the "off" rider 54 clamped at five-thirty on the dial will strike the transverse projection 61 of the member 60, thereby stretching the spring 63. Finally, the member 60 will have been rotated so far that the projection 61 rides off the rider 54 while bearing upward against the rider 54, thus forcing the member 51 downward with a snap action, the time now being five-thirty. The movement of the member 51 opens the switch contacts 71-72 to disconnect the water heater 15 and shifts the bell-crank lever 43 to move the target 36 to the black 42 and to bring the gear 31 into mesh again to drive the black-pointer dial 24. It will be understood that additional "on" and "off" riders may be provided for either filling in additional valleys in the load curve or for the purpose of preventing connection of the water heater 15 during peaks in the daily load curve.

Water heaters and other devices of like character are ordinarily so designed that they need not operate continuously and, since the heat is stored, it is immaterial whether they are connected during one time of the day or another. Consequently, it is desirable to provide apparatus for connecting a water heater at times of the day which will be most profitable to the central station and will permit giving the customer a rate reduction. However, the apparatus is useful also in case no load is to be controlled but different rates at different times of the day are desired.

In case of voltage failure which would stop or interrupt the operation of the time switch 13 energized by the voltage of the current source and which might be of such long duration as to cause the time indication of the time switch to be several hours slow, it is obvious that the time switch unit without the time delay transfer mechanism 10 might cause the high rate register 24 to be connected during the various hours of the day when the customer is entitled to the low rate, and during which the customer might have been drawing large loads upon the inducement of the central station company to offer low rates at certain times of the day. To guard against this unjust billing in case of voltage failure or interruption in operation of the time switch unit, the failure of voltage energizing the time switch unit 13 causes the coil 107 to be deenergized and to cool off permitting the strip 100 to cool and release the latch 99, whereupon the spring 122 moves the lever 119 to a downward or counter-clockwise angular position, moving the pin 105 to the left and also sliding the end of the lever 93 off the tip 95 of the lever 58', thus freeing the tip 95 to permit the shift lever 58' to move in a clockwise direction, with the pin 59 moving to the right under the influence of the spring 98, and causing the low rate register 25 to come into engagement and remain in engagement regardless of subsequent angular positions of the bushing 55 produced by the time switch unit 13. Subsequent energization of the heater coil 107 upon recovery of voltage will cause the strip 100

5 to bend downward again but cannot cause re-entry of the latch 99 into the slot 101.

The mechanism is so adjusted that if the power interruption has been of an inconsequentially short duration, e. g., less than five minutes or any other predetermined period, the strip 100 does not cool sufficiently to unlatch the latch 99. The magnitude of time delay is determined by the design of the parts with suitable thermal conductivity and heat capacity, e. g., by making the high-rate release strip 100 of appropriate length and thickness. The time delay obtained may also be adjusted by varying the position of the heater coil 107 on the bracket 108 and by adjustment of the screw 113. Thus any desired period of time delay may be obtained.

After normal voltage conditions have been restored on the lines of the power station and when the power station has sent a representative to reset the time switch 13 in accordance with the correct time, such representative will depress the adjusting knob 76 in order to set the time switch. Simultaneously by reason of the engagement of the cone-shaped enlargement 118 and the arm 119, the member 91 will be reset to the normal clockwise angular position thereby moving the pin 105 against the inside edge 106 of the elbow of the shift lever 58' and bringing the holding lever 93 in position in which the notch 94 would engage the tip 95, thereby making the shift lever 58' and the crank 96 a rigid unit again. The voltage having been restored, the right-hand end of the strip 100 is in the downward position so that the latch 99 snaps into the slot 101 when the member 91 is rotated by the action of the cone 118. However, in case the central station representative attempts to reset the mechanism before the voltage has been restored, the member 100 will remain up in an upwardly bent position and the member 91 will drop back to the low rate position as soon as the adjusting knob 76 is released.

In accordance with the provisions of the patent statutes, we have described the principle of operation of our invention together with the apparatus which we now consider to represent the best embodiment thereof but we desire to have it understood that the apparatus shown is only illustrative and that the invention may be carried out by other means.

What we claim as new and desire to secure by Letters Patent of the United States is:

1. Apparatus for metering at differing rates two classes of load supplied by a common power source and controlling one of the classes of load according to the time, said apparatus comprising in combination, a power-responsive integrating mechanism including input terminals for electrical connection to a power source, output terminals for continuous electrical connection to a load of one class and intermittent connection to a load of a second class, a low rate register dial and a high rate register dial, a time switch unit energized by the power source, and having a movable member adapted to be moved to one or the other of two alternative positions according to the time, relatively movable switch contacts in operable relation with said movable member for connecting and disconnecting a load of the second class to and from the said output terminals, alternative connecting means for forming a driving connection between said integrating mechanism and one of the other of said registers, an operating connection between the movable member of the time switch and the said alterna-

tive connecting means, and means responsive to power failure for rendering the said operating connection ineffective and maintaining the low rate dial in operation.

2. In a dual rate meter including power-responsive integrating mechanism, a rotatable shaft carrying a worm wheel, a low rate register dial and a high rate register dial each including a driving shaft carrying a worm gear adapted alternatively to mesh with said worm wheel, a time switch unit adapted to be energized by a source of power and having a movable member adapted to be moved to one or the other of two alternative positions according to the time, and supports for said dial shafts with a connection to said movable member in such relation as to cause one of said gears to mesh with said worm wheel when said movable member is in one position and to cause the other of said gears to mesh with said worm wheel when the movable member is in the other of its positions, said connection including an element electrically connected to the time switch unit and normally energized by the same power source energizing the time switch unit for normally maintaining the said connection effective, and means for rendering the connection between said supports and said movable member ineffective in response to interruption of the power source energizing the time switch unit and the first said element included in said connection, said connection also including another element for resiliently biasing the supports for said dial shafts to the position in which the low rate register dial is driven.

3. A dual rate meter including a low rate register dial and a high rate register dial, alternative driving connections to said register dials, a time switch unit for normally putting one or the other of said connections into effect according to the time, means for resiliently biasing the apparatus to the low rate connection, a power source for the time switch unit, and means normally energized by the same source and responsive to power failure for making the time switch unit ineffective to control said driving connection and leaving continuously effective the driving connection to the low rate register dial.

4. In a dual rate meter including a power responsive integrating mechanism, a low rate register dial and a high rate register dial, each adapted to be driven by the integrating mechanism, alternative driving connections to said register dials, a time switch unit with energizing connections, shift mechanism normally operated by the time switch unit for making one or the other of said connections effective according to the time, and means connected to said energizing connections and responsive to interruption in energization for operating the shift mechanism to its condition effecting the connection between the integrating mechanism and the low rate register dial.

5. In a dual rate integrating meter, a low rate register dial and a high rate register dial, alternative driving connections to said register dials, a controller member having alternative conditions of operation in which it makes one or the other of said alternative driving connections effective, a selector for normally shifting said controller to one or the other of its operating conditions, and means with a power source for normally maintaining it inactive but responsive to power failure for transferring the controller to its condition effecting the driving connection to the low rate register dial,

6. In a dual rate meter including a low rate register dial and a high rate register dial, alternative driving connections to said dials, one or the other of which is adapted to be effective according to the position of a shift lever, the combination of a jointed shift lever having an operating end and a driven end with a joint between, a time switch unit adapted to move the driven end of the shift lever to one or the other of two alternative positions according to time, normally effective mechanism for maintaining said shift lever stiff so that its operating end follows the motion of the driven end, and means normally energized for normally maintaining said mechanism effective and responsive to interruption in energization for releasing the joint of said shift lever and maintaining the operating end of the shift lever continuously in the position effecting connection to the low rate register dial.

7. In a dual rate meter including a low rate register dial and a high rate register dial with driving connections to said dials adapted to be made alternatively effective in accordance with the position of the operating end of a shift lever, the combination of a shift lever having an operating end and a driven end with a jointed connection therebetween, a time switch unit attached to the said driven end for shifting its position according to the time of day and adapted

25 to be energized by a source of current to be metered by the dual rate meter, means for resiliently biasing the operating end of the shift lever to the position in which the driving connection to the low rate register dial is effective, and an electroresponsive latching device for normally, when energized, maintaining effectively rigid the jointed connection of said shift lever to overcome the effect of the said biasing means and cause the operating end of the shift lever to move in response to the motion of the driven end thereof, said latching device being connected for energization by the same current source as the time switch unit and being adapted, when deenergized, to release said jointed connection.

40 8. In a dual rate meter including a low rate register dial and a high rate register dial with driving connections to said dials adapted to be made alternatively effective in accordance with the position of the operating end of a shift lever, the combination of a shift lever having an operating end and a driven end with a jointed connection

50 therebetween, a selector connected to the driven end of the shift lever for shifting its position back and forth for selecting one register or the other and adapted to be energized by a source of current to be metered by the dual rate meter, means for resiliently biasing the operating end of the shift lever to the position in which the driving connection to the low rate register dial is effective, and a bimetallic latching device

55 60 for maintaining rigid the jointed connection of said shift lever to overcome the effect of the said biasing means and cause the operating end of the shift lever to move in response to the motion of the driven end thereof, a current responsive heater in thermal connection with said bimetallic latching device, said latching device being so mechanically connected as to bend when heated into the position in which the latch may be engaged and to release the latch when cooled, said heater being electrically connected to the energizing source for said selector.

65 70 75 9. In a dual rate meter including a low rate register dial and a high rate register dial, alternative driving connections to said dials, one or

the other of which is adapted to be effective according to the position of a shift lever, the combination of a jointed shift lever having an operating end and a driven end, a time switch unit adapted to move the driven end of the shift lever to one or the other of two alternative positions according to time, said time switch unit having energizing connections, normally effective means for maintaining said shift lever stiff so that its operating end follows the motion of the driven end, means for releasing the joint of said shift lever and maintaining continuously the connection to the low rate register dial in response to interruption in energization of the time switch unit, and means for readjusting the time setting of the time switch unit after interruption thereof and simultaneously resetting the rigid connection between the parts of the shift lever.

10. In combination, a timer, a shift lever adapted to be moved to one or the other of two alternative positions in accordance with time, means resiliently biasing said shift lever to one of its alternative positions, mechanism for connecting said timer to said shift lever, and normally energized means associated with said mechanism for normally maintaining it effective and responsive to interruption in energization for disconnecting said connecting mechanism.

11. In combination, a timer, a shift lever adapted to be moved to one or the other of two alternative positions in accordance with time, means resiliently biasing said shift lever to one of its alternative positions, mechanism including

5 a latch for connecting said timer to said shift lever, said connecting mechanism having connecting and disconnecting positions in which the connection is respectively effective and ineffective between the timer and the shift lever, and normally energized means adapted, while energized, to engage said latch and hold the connecting mechanism in the connecting position when the mechanism is moved thereto and responsive 10 to interruption in energization for releasing said holding means and unlatching said connecting mechanism.

12. In combination, a normally energized timer, a shift lever adapted to be moved to one or the other of two alternative positions in accordance with time, means resiliently biasing said shift lever to one of its alternative positions, mechanism including a latch for connecting said timer to said shift lever, said connecting mechanism having connecting and disconnecting positions, normally energized means adapted, while energized, to engage said latch and hold the connecting mechanism in the connecting position when the mechanism is moved thereto, and responsive 20 to interruption in energization for releasing said holding means and unlatching said connecting mechanism, and means for resetting said timer to the correct time and simultaneously resetting said connecting mechanism to the latched position after an interruption in energization.

HERBERT H. ANDERSEN.
DONALD G. CAMERON.

CERTIFICATE OF CORRECTION.

Patent No. 2,285,882.

June 9, 1942.

HERBERT H. ANDERSEN, ET AL.

It is hereby certified that error appears in the printed specification of the above numbered patent requiring correction as follows: Page 5, first column, line 26, claim 2, for "effective, and means for" read --effective and for--; and that the said Letters Patent should be read with this correction therein that the same may conform to the record of the case in the Patent Office.

Signed and sealed this 4th day of August, A. D. 1942.

Henry Van Arsdale,

Acting Commissioner of Patents.
